BRAKE SHOE

Albert Nelson, Chicago, Ill., assignor to The American Brake Shoe and Foundry Company, New York, N. Y., a corporation of Delaware

Application February 1, 1937, Serial No. 123,345

1 Claim. (Cl. 188—258)

This invention relates to certain novel improvements in brake shoes of the kind used on railway equipment and more particularly to cast metallic shoes adapted for such usage.

5 A brake shoe of the kind to which this invention pertains is substantially rectangular in plan and of arcuate shape longitudinally and is provided on its back midway between its ends with a center attaching lug and at its ends on its back with what 10 are called end stops. This lug and these stops cooperate with complementary parts on a head that is part of the brake rigging when the shoe is keyed or otherwise secured to the head to retain the shoe in operative position and to this end 15 the inwardly disposed faces of the end stops are spaced from the center attaching lug in an amount specified by present A. R. A. regulations.

The longitudinal thrust on the shoe in a braking operation effected by engaging the wearing 20 face of the shoe with the tread of the wheel is for the most part impressed on the end stops which also serve to prevent sidewise movement of the shoe in the head. It will therefore be appreciated that the end stops are subjected to severe strains 25 in use.

Furthermore it is customary to chill the ends 30 of a brake shoe, especially on the wearing face, as it is cast, wherefore the ends of the shoe underlying the end stops are rendered more frangible than the other portions of the shoe. It is therefore an advantage to provide substantial end 35 stops at the ends of the shoe for so to do affords reinforcement for the more frangible portions and mitigates against fracture and kindred damage.

Thus relatively large end stops are desirable but the fixed dimensions of the parts of the head with which the stops cooperate when the shoe is installed, requiring spacing of the inwardly disposed faces of the end stops from the center attaching lug in an amount specified by present 40 A. R. A. regulations, prevent enlargement of the stops inwardly of the shoe. It is of course possible to increase the size of the stops outwardly of the shoe but so to do longitudinally would ordinarily require lengthening of the over-all length of the shoe especially on its wearing face. This, however, would be objectionable for several 45 reasons not the least of which would be that such procedure would require larger flasks than are now employed in the casting of shoes. Makers of brake shoes have on hand a very large number of flasks suitable for shoes of the present wearing 50 face length and such flasks would be rendered 55

useless if a shoe having a longer wearing face than the present shoe was to be cast.

Thus in view of the foregoing the salient object of this invention is to enlarge the end stops customarily provided on a brake shoe, especially longitudinally of the shoe, without increasing the length of the wearing face of the shoe.

A reenforcing back customarily in the form of a steel plate is often provided at the back of a brake shoe and a bundle of expanded metal is often incorporated in such a shoe. To insure the flow of sufficient metal past the ends of such back and bundles to form the end stops, such backs and bundles are terminated inwardly of the ends of the shoe with the result that the reenforcing 15 backs usually project but a very short distance under the end stops which as a result are not as effectively reenforced by the back as they would be if the back projected thereunder for a substantial distance.

Therefore still another object of this invention is to enable the reenforcing back customarily provided in a brake shoe to be projected well toward the ends of the shoe so that it will underlie and effectively reinforce the end stops provided 20 on the back of the shoe at its ends, and an ancillary object is to afford anchorage through the back for the end stops.

Other objects are included in the following description wherein reference is made to the accompanying drawing in which

Fig. 1 is a side elevation of a brake shoe made in accordance with my invention;

Fig. 2 is a top plan of the shoe shown in Fig. 1; Fig. 3 is a vertical transverse sectional detail 35 view taken substantially on the line 3—3 on Fig. 2;

Fig. 4 is a horizontal sectional detail view taken substantially on the line 4—4 on Fig. 3;

Fig. 5 is a fragmentary view, similar to Fig. 1, 40 showing the end of a standard brake shoe;

Fig. 6 is a fragmentary top plan of a modified form of a reenforcing back and wherein the outlines of a brake shoe embodying such back are shown in broken lines; and

Fig. 7 is a fragmentary view, similar to Fig. 1, 45 of a shoe embodying the back illustrated in Fig. 6.

My novel shoe as illustrated in the accompanying drawing comprises a body 6 preferably of cast iron and has a reenforcing back 7 preferably 50 in the form of a steel plate embedded therein at the rear face thereof. As best shown in Figs. 1 and 2 the shoe is substantially rectangular in plan and of arcuate shape longitudinally to provide a wearing face at its front adapted to co- 55

operate with the tread of a wheel in a braking operation.

Midway between its ends and on its rear face the shoe is provided with a center attaching lug 8 in the form of a steel strap bent to provide vertically extending legs which project through openings in the back 7 and have their ends in-turned toward each other to thereby connect the strap to the reenforcing back. Preferably the body is extended upwardly to enclose the side edges and outer faces of the vertically extending legs of the strap providing the attaching lug 8. A portion 9 of the body is extended between the adjacent faces of said vertically extending legs immediately above the reenforcing back 7 to reinforce the portions 10 (Fig. 4) of the body outwardly of the side edges of the vertically extending legs to prevent breaking away of these portions 10. An opening defined by the strap 8 and the upper wall of the portion 9 is of sufficient size to enable a key or other attaching means to be passed therethrough to secure the shoe in operative position in the usual head that is a part of the brake rigging of railway equipment.

At each end and on its back the shoe is provided with substantially T-shaped end stops 11, the stems 12 of which extend inwardly of the shoe substantially midway between the side edges thereof. These end stops are disposed in such positions on the back of the shoe that the inwardly faced edges of these stops are in position to properly cooperate with the head when the brake shoe is placed on the head and to this end the inwardly disposed faces of the end stops are spaced from the center attaching lug in the amount specified in present A. R. A. regulations. It has been customary to provide openings as 13 in the reenforcing back 7 so that the metal providing the stems 12 will be united with the body of the shoe by a section of metal in these openings 13. This arrangement affords reenforcement for the stems 12 of the end stops but the branches or cross members of the end stops on which most of the thrust is impressed in a braking operation are not materially reenforced by this arrangement.

Thus it is proposed to enlarge the cross members of the end stops 11 so as to strengthen these members and consequently the end stops as a whole, and in the present instance this has been done by elongating the end stops longitudinally of the shoe.

It has been explained that it is objectionable to elongate the wearing face of a brake shoe and thus in my novel shoe, even though the end stops are elongated, elongation of the wearing face is avoided by alteration of the ends of the shoe, the standard arrangement for the ends of a shoe being shown in Fig. 5. By referring to Fig. 5 it will be seen that the end of the standard shoe lies in a plane extended in angular relation with respect to the face of the shoe, the angularity between the end and the face of the shoe being materially less than a right angle.

In contradistinction to this in my novel shoe a part of the end of the shoe lies in a plane extended from and in substantially right angular relation with the wearing face of the shoe for an appreciable distance away from the wearing face of the shoe, that is to say, to a position disposed a short distance below the plane of the back of the shoe. The remaining part of the end of the shoe is then arranged to lie in an inwardly extending plane, the outer ends of the end stops also lying in this plane. Thus the end of the shoe lies

in two angularly disposed planes, one of which is arranged substantially in right angular relation with the face of the shoe and the other of which projects inwardly at substantially a 165° angle with respect to the substantially right angularly extending plane, the apex between the planes being located somewhat below the plane of the back of the shoe substantially in alignment with the reenforcing back 7. This arrangement enables elongation of the end stops on the back 10 at the end of the shoe, with the inwardly disposed faces of the end stops in the position specified by present A. R. A. regulations, without an increase in the length of the wearing face of the shoe and with but a very small increase in the over-all 15 length of the shoe wherefore elongation of the end stops is accomplished, but the objections which would be attendant to an increase in the length of the shoe, especially at its wearing face, such as rendering present flasks useless, are 20 avoided.

By referring to Fig. 1 wherein a reenforcing back of a length corresponding to that employed in a standard shoe is shown, it will be noted that there is appreciable metal between each end of 25 the back and the adjacent end of the shoe. In fact, substantially twice as much metal as ordinarily provided is present as will be seen by comparison of the shoe in Fig. 1 with that shown in Fig. 5. This affords very firm anchorage for 30 the end stops and substantially increases the strength thereof.

However, as shown in Fig. 7, it is possible to use a back longer than is customary in my novel shoe, and thereby reenforce the end stops, and 35 when such a longer back is provided it is arranged to terminate in spaced relation with the ends of the shoe in an amount substantially equal to the spacing of the usual back from the ends of a standard shoe. This spacing enables sufficient 40 metal to flow past the ends of the back in the casting operation to insure proper formation of the end stops.

However, when such elongation of the back is resorted to, it is preferable and advantageous to 45 afford additional reenforcement for the end stops and this may be accomplished by providing an opening as 13' in the elongated back indicated by 14. The longitudinally elongated openings 13' are located in the back 14 in positions similar to 50 the location of the openings 13 in the standard back 7. But in addition to the openings 13', longitudinally elongated openings 15 may be provided at each side of the openings 13'. The openings 15 will underlie the cross or branch members 55 of the end stops and will afford anchorage for these members inasmuch as the stops will be united with the body of the shoe by metal extending through the openings 15.

It will therefore be seen that substantial or 60 enlarged end stops may be provided on the back of a brake shoe at its ends without elongation of the wearing face of the shoe or substantially increasing the over-all length of the shoe and that when a standard length back is employed 65 in a shoe having such enlarged end stops the additional metal between the ends of the back and the ends of the shoe effectively reenforces the end stops. It will also be seen that such enlargement of the end stops enables a longer re-enforcing back than has heretofore been employed to be provided at the rear face of the shoe wherefore the back will underlie and afford re-enforcement for the end stops. Furthermore, not only will such an elongated back reenforce 70

the end stops but by providing openings in such a back firm anchorage through the back for the end stops may be afforded especially by properly locating the openings in the back.

5 Furthermore, such enlargement of the end stops is accomplished in accordance with my invention by varying the formation of the ends of the brake shoe and instead of arranging the ends in single planes extending at acute angles with
10 respect to the wearing face of the shoe the ends are arranged in two intersecting angles, the apex between which is disposed somewhat below the plane of the back of the shoe, and one of these planes is arranged to extend substantially at
15 right angles to the wearing face of the shoe and the other plane is arranged to project inwardly from such right angularly extending plane at a relatively large obtuse angle.

While I have illustrated and described a preferred form of my invention it is to be understood that this is capable of variation and modification and I therefore do not wish to be limited to the precise details set forth but desire to avail myself of such changes and alterations as fall
25 within the purview of the following claim:

I claim:

A brake shoe having a center attaching lug on its back midway between its ends and end stops on said back at the ends of the shoe, each of said
30 end stops being substantially T-shaped in formation and having the outwardly disposed end thereof lying in the adjacent end of the shoe and

having the inwardly disposed faces of the branches thereof spaced from the center attaching lug in the amount specified by present A. R. A. regulations, each of the ends of the shoe having two angularly disposed faces, one of the faces at 5 each end of the shoe extending from the wearing face in substantially right angular relation with said wearing face and the second of the faces at each end of the shoe extending inwardly of the shoe at substantially a 165° angle with respect to 10 the other face whereby the branches of the end stops are of substantial size, and a reenforcing back embedded in the shoe at its rear face and having the ends thereof spaced inwardly but a short distance from the intersection of the faces 15 at each end of the shoe, said back having an opening therein at each end thereof disposed entirely beneath the stem of the adjacent end stop and other openings therein respectively positioned on opposite sides of the first openings, said 20 other openings being disposed partly beneath the branches of the end stops and in transverse alignment with the first openings, the body of the shoe being united with said end stops through said openings, the angular inclinations of the faces 25 of the ends of the shoe, the extension of said back beneath the end stops and the connection of said end stops with the body of the shoe through said openings effectively reenforcing said end stops.

ALBERT NELSON.
